GLOVE LINING FORM

Edwin B. Newton, Akron, Ohio, assignor to The
B. F. Goodrich Company, New York, N. Y., a
corporation of New York

Application April 11, 1933. Serial No. 665,529

4 Claims. (Cl. 154—1)

This invention relates to forms used in the manufacture of rubber articles and especially forms adapted to support a rubber glove or similar article while a lining is being applied thereto.

It has been found desirable to provide certain rubber gloves and similar articles with an absorbent and insulating lining so that perspiration will be absorbed, the article may be applied or removed with ease, and heat will be retained in the hand. Heretofore, as far as I am aware, the preferred practice in lining such gloves has been to support the glove on a form which contacts with the entire inner surface of the glove when the glove is inside out, and then reversing the glove to bring the lining on the inside of it. Cement is applied over the surface of the glove and a fabric lining having the shape of the glove is drawn thereover. In placing the fabric lining the cement is often scraped from the glove, resulting in poor adhesion, especially in the region of the fingers.

The principal objects of this invention are to permit placing of the lining without objectionable removal of the cement coating and with the exercise of a minimum amount of force.

Other objects will appear from the following description and the accompanying drawing.

In the drawing:

Fig. 1 is a front elevation of the form with a glove and lining thereon, part of the glove and lining being broken away.

Fig. 2 is a cross-section taken on line 2—2 of Fig. 1.

Fig. 3 is a cross-section taken on line 3—3 of Fig. 1.

Fig. 4 is a cross-section taken on line 4—4 of Fig. 1.

Referring to the drawing, the numeral 10 designates a substantially rigid form, which may be made of metal, thermoplastic rubber, vitreous or other material, having the general shape of the glove to be lined. At the wrist portion it is formed with a groove 11, preferably extending entirely around the form. A series of depressions or grooves 12, 13, 14, 15, and 16 extend lengthwise of the fingers and thumb, connecting with groove 11 and extending to the tips of those members and preferably continuing down the opposite side thereof to again join the groove 11. One or more perforations 17 are formed at the bottom of the depressions or grooves and communicate with the interior of the hollow form.

The form is closed at its gauntlet end except for a single opening 18 to which is attached a pipe 19 which may be connected to a vacuum

pump or other source of sub-atmospheric pressure or to a pressure air supply at will.

In the use of the device a rubber glove 20 is placed on the form. Pipe 19 is connected to the source of low pressure and the form is evacuated, causing those parts of the glove which overlie the grooves to be collapsed into conformity to the grooves. A coating of unvulcanized rubber 21 is now applied to the form by painting, spraying, or dipping the article with a dispersion of rubber composition in water or an organic solvent.

The fabric lining 22, which previously had been constructed and wet with a rubber solvent, is now drawn over the rubber glove. As it does not contact with those coated portions of the glove which lie within the grooves in the form, the coating of such portions is undisturbed. When the lining is in place, air under pressure is admitted to the form through the pipe 19, causing those portions of the glove at the positions of the grooves to be pressed into contact with the lining without shearing movement.

The provision of the grooves extending to the tips of the fingers and over two opposite faces thereof prevents the cement being disturbed over those areas and therefore provides a zone of superior adhesion extending over the areas occupied by the grooves and insures adequate adhesion of the lining at the finger tips of the glove, and the reduction of the length of the general cross-sectional outline of the several elements of the form incident to the presence of the grooves permits the drawing of the lining onto the glove without such tightness of fit as to wipe the cement from the glove to an excessive degree even as to those areas in which the glove wall is in its normal position.

I claim:

1. A form for use in applying a facing layer to a rubber article comprising a hollow body having the general shape of the article and adapted for the article to be drawn thereover, said form having a depression in its outer surface adapted to be sealed by an article when in place on the form, and means to evacuate the depression to draw thereinto a portion of the article overlying the depression.

2. A form for supporting a glove to be provided with a lining, said form comprising a hollow body having the general shape of the glove, said form having grooves extending along the fingers thereof and adapted to be sealed by a glove when the latter is in place on the form, and means for de-

pressing portions of the glove overlying the grooves.

3. A form for supporting a glove to be provided with a lining, said form comprising a hollow body having the general shape of the glove, said form having grooves in its outer surface extending along the fingers and over the tips thereof and adapted to be sealed by a glove when the latter is in place on the form, and means for depressing portions of the glove overlying the grooves.

4. A form for supporting a glove to be provided

with a lining, said form comprising a body having the general shape of a glove, said form having a depression in its outer face extending over a portion of the form where maximum adhesion of glove and lining is desired, and means for producing a sub-atmospheric pressure in said depression when the form is covered by a glove to depress a portion of the glove while a lining is being applied thereto.
